Primary Examiner — Anhdao Doan*Assistant Examiner* — Mary Malley(74) *Attorney, Agent, or Firm* — Chris J Katopis(57) **CLAIM**

The ornamental design for a glove-based device controller, or portion thereof, as shown and described.

DESCRIPTION

FIG. 1 is a perspective view of a glove-based device controller, showing my new design;

FIG. 2 is a top plan view thereof;

FIG. 3 is a bottom plan view thereof;

FIG. 4 is a side elevation view thereof;

FIG. 5 is an opposite side view thereof;

FIG. 6 is a front view thereof; and,

FIG. 7 is a rear view thereof.

The broken lines immediately adjacent to the shaded areas represent the bounds of the claim, and all other broken lines represent the environment. The broken lines form no part of the claimed design.

1 Claim, 5 Drawing Sheets(56)
